UNITED STATES PATENT OFFICE.

DAVID A. KENNEDY, OF LEXINGTON, VIRGINIA, ASSIGNOR OF ONE-HALF
TO JOSEPH KENNEDY, OF SAME PLACE.

MEANS FOR SECURING THE CUTTERS OF HARVESTERS TO THE CUTTER-BARS.

SPECIFICATION forming part of Letters Patent No. 269,062, dated December 12, 1882.

Application filed June 6, 1882. (No model.)

To all whom it may concern:

Be it known that I, DAVID A. KENNEDY, a citizen of the United States of America, residing at Lexington, in the county of Rockbridge 5 and State of Virginia, have invented certain new and useful Improvements in the Means for Securing the Cutters of Harvesters to the Cutter-Bars; and I do hereby declare the following to be a full, clear, and exact description of the invention, such as will enable others skilled in the art to which it appertains to make and use the same.

This invention relates to improved means for securing the cutters of harvesters to the 15 cutter-bars; and its object is to provide a simple and reliable means for attaching singly each cutter in such manner that each cutter may be attached and released independently of the others.

20 My invention therefore consists in a harvester-cutter having the shank made with the usual beveled edges, and formed with a beveled wedge-shaped recess in the rear of the shank, for the purpose hereinafter set forth.

25 My invention further consists of a cutter-bar of a harvester provided with the usual beveled recesses on its face to receive the cutters, and formed with vertical wedge-shaped recesses in the rear side registering with the 30 wedge-shaped recess in the cutter.

My invention further consists in the novel construction, combination, and arrangement of parts, as will be hereinafter more specifically described and claimed.

35 In the accompanying drawings, forming a part of this specification, Figure 1 represents a perspective view of the cutter-bar, cutter, and fastening-key. Fig. 2 represents the cutter; and Fig. 3 is a perspective view, showing 40 the parts joined.

The letter A represents the cutter-bar having cut or formed in its upper face the transverse beveled recesses *a* to receive the shanks of the cutters, and formed with beveled wedge-shaped recesses *b* in the rear face of the bar, centrally located in the transverse beveled recesses in the face.

The letter B represents the cutter, formed, so far as the blade is concerned, as may be de-

sired, and having the shank made with beveled edges fitting the beveled recesses in the cutter-bar, and also formed with a beveled wedge-shaped recess, *b'*, in the rear of the shank corresponding to the beveled wedge-shaped recesses formed or cut in the rear side of the 55 cutter-bar.

The letter C represents a wedge made with beveled edges and fitting flush in the recesses of the shank of the cutter and cutter-bar.

It will be observed that the vertical recesses 60 of the cutter-bar are made slightly flared at the lower portions, the object being to admit of slightly spreading the key on the lower side, so as to prevent it from working out, and yet not sufficient to prevent its being drawn out 65 and used again. To better secure the cutters to the cutter-bar it is advisable, after the key is driven home, to upset the metal thereof by hammering or otherwise, so as to fill the angles of the cutter and cutter-bar, substantially 70 as seen in Fig. 3 of the drawings, to prevent any displacement of the fastening-key; but the upsetting should not be of such positive character as to prevent the removal of the key for 75 repairs as required. To unite and secure the 75 parts, the cutter is slipped in the beveled recess in the cutter-bar until its shoulders set against the forward face thereof, and then the wedge is inserted in the vertical rear recess and driven home, thereby securing the cutters to 80 the bars. It will be observed that by these means of fastening each cutter is independently secured, and may be separately removed 85 without disturbing the rest of the cutters.

I do not claim broadly the construction of the 85 cutter-bar with transverse beveled recesses in the upper face, nor the cutters formed with the shanks beveled to fit the transverse recesses of the cutter-bar, as both of these have been heretofore in use; but my invention is to form 90 vertical beveled wedge-shaped recesses in the rear of the cutter-bar and shank of the cutter adapted to receive and retain a wedge or key beveled on the edges.

By the means herein described and shown 95 the cutter and bar are held from displacement in every direction and under all circumstances, whether the strain be upward or downward,

forward or rearward, and the combination of parts secured as stated meets every exigency which can reasonably happen.

What I claim as my invention, and desire to secure by Letters Patent, is—

1. A harvester-cutter the shank whereof is formed with beveled edges and a vertically-beveled wedge-shaped recess in the rear of the shank, substantially as described, and for the purpose set forth.

2. A harvester cutter-bar formed with beveled recesses on its face adapted to receive the shanks of the cutters, and formed with vertically-beveled wedge-shaped recesses in the rear face thereof, substantially as described, and for the purpose set forth.

3. The cutters provided with beveled edges and vertically-beveled wedge-shaped recesses in the rear of the shanks, in combination with the cutter-bar having vertically-beveled wedge-shaped recesses on the rear side, and wedge-shaped keys adapted to fit in the vertically-beveled wedge-shaped recesses of the cutter and bar, substantially as described.

In testimony whereof I affix my signature in presence of two witnesses.

DAVID A. KENNEDY.
